TOOL

Robert Lack, Pomona, Calif.

Application January 4, 1938, Serial No. 183,379

2 Claims. (Cl. 33—189)

The invention relates to a tool and more particularly a combination center head level and bevel protractor.

The primary object of the invention is the provision of a tool of this character, wherein the same is adaptable for laying out a line for a key way, groove or hole or a series thereof in a shaft, rod or the like with trueness and accuracy.

Another object of the invention is the provision of a tool of this character, wherein the construction thereof is novel in its entirety and is susceptible of easy handling, being susceptible of receiving the shaft, rod or the like without the necessity of reversing the latter in the laying out 15 of key seats at opposite ends thereof and also can be used as a double edged protractor.

A further object of the invention is the provision of a tool of this character, which is simple in construction, thoroughly reliable and effective 20 in operation, readily and easily handled, susceptible of quick adjustment, compact, strong, durable and inexpensive to manufacture.

With these and other objects in view, the invention consists in the features of construction, 25 combination and arrangement of parts as will be hereinafter more fully described, illustrated in the accompanying drawings, which disclose the preferred embodiment of the invention and pointed out in the claims hereunto appended.

30 In the accompanying drawings:

Figure 1 is an elevation of the tool constructed in accordance with the invention and being partly in section.

Figure 2 is an elevation looking toward the opposite side thereof.

Figure 3 is a sectional view on the line 3—3 of Figure 2 looking in the direction of the arrows.

Figure 4 is a sectional view on the line 4—4 of Figure 2 looking in the direction of the arrows.

40 Figure 5 is a view similar to Figure 1 showing the tool converted for service as a double edged protractor.

Similar reference characters indicate corresponding parts throughout the several views in 45 the drawings.

Referring to the drawings in detail, A designates generally the tool in its entirety constructed in accordance with the invention and involves a plate-like body 10, preferably made from 50 metal, having the rounded opposite ends 11 and is of elongated formation. Provided adjacent to one end of this body 10 and formed transversely therethrough is a shaft-receiving opening 12 of a size to accommodate shafts, rods or the like of 55 varying diameters to a determined maximum.

The opening 12 next to a longer edge thereof merges into a V-formed recess 13 while threaded into the body 10 through the opposite longer edge for projection into the opening 12 diametrically opposite the recess 13 is a set screw 14 for engagement with a piece of work, such as a shaft, rod or the like 15 when passed through the said opening 12 and centered by the said recess 13.

Axially aligned with the set screw 14 and tapped into a suitable hole 16 in the body 10 is a punch 10 guide barrel 17 which projects laterally from the body while held within this barrel is a spring tensioned punch 18, its stem 19 being slidably fitted in the barrel and has the coiled tensioning spring 20 for the punch 18 surrounding it. 15 The outer end of the stem 19 of the punch 18 projects outwardly of the barrel and carries at this projected end a finger hold or grip 21 so that by pulling outwardly upon the latter and then relieving the same the spring 20 tensioning 20 the punch 18 will drive the same into the work 15 for the marking thereof when held by the set screw 14 centered in the recess 13 and within the opening 12 in the body 10.

The body 10 at the end having the opening 12 25 has a thickened area 22 concentrically about the said opening 12 and projects outwardly from one side of the said body for the strengthening of the latter at this area.

Close to the other end of the body 10 to be disposed at one side of the opening 12 is a turntable turret 23, being fitted in a clearance therefor provided in said body 10 and carries a horizontal spirit level 24. The turret 23 is provided with an open center 25 and at one side of said turret is 35 provided a protractor sector 26 graduated for one-half of the circulatory formation of the turret 23 and these graduations begin at zero and end with one hundred and eighty degrees for co-action with pointers or indicator marks 27 upon 40 the body 10 at diametrically opposite points with respect to the said turret 23. The center of the turret is at the longitudinal center of the body 10 and similarly the center of the opening 12 is at the longitudinal center of the said body 10. 45

The turret is also formed with a laterally offset guide 27 for a rule blade 28 having the usual lineal scales 29 and 30, respectively, thereon, the guide being fitted with a lock 31 for adjustably locking the rule blade 28 in the use thereof. 50

The guide 27 is on the side of the turret 23 opposite to the side carrying the horizontal spirit level 24.

In the use of the tool for laying out key seats at opposite ends of a long shaft where it is not 55

possible to cut both key seats without reversing the shaft, the turret 23 is set at zero, the turret being adjustably held by a knurled lock 32 and is locked at zero. The turret is now placed on the work, such as a shaft, rod or the like 15, and revolved about the latter until the bubble in the level 24 is in position whence the set screw 14 clamps the work holding the tool and shaft fixed relative to each other. Now by snapping the punch 18, a dot is placed on the shaft in that the punch will strike and mark said shaft when snapped. This operation is repeated at the opposite end of the shaft, rod or the like and the two markings will align with each other. The tool is susceptible for use in laying out splined shafts and in the laying of ten splines the turret will have been turned thirty-six degrees and thereafter the tool revolved on the shaft until the bubble in the level 24 is in position again. It is possible to have the tool remain secured on the shaft, rod or the like and the shaft revolved in a shaper or milling machine. Now to use the tool as a double edged protractor, the barrel 17 with the punch 18 therein is detached and also the set screw 14 is removed whereupon the rule blade 28 is placed in the guide 27' on the turret and such tool is now converted for the use thereof as a double edged protractor.

The tool is susceptible for use in setting the timing on engines any number of degrees before or after dead center by clamping it to the crank shaft of the engine.

What is claimed is:

1. A tool of the kind described comprising a body having a work-receiving opening wholly within the same and also a V-shaped notch communicative with the work-receiving opening, a punch guide barrel connected with the body and opening into the notch, a punch slidably fitted within the barrel for projection into the V-shaped notch, spring tensioning means confined within the barrel and active upon the punch for projecting the same into the notch, and a clamping screw fitting the body for axial alignment with and directly opposite the punch to be projected into the opening in said body. 5 10

2. A tool of the kind described comprising a body having a work-receiving opening wholly within the same and also a V-shaped notch communicative with the work-receiving opening, a punch guide barrel connected with the body and opening into the notch, a punch slidably fitted within the barrel for projection in to the V-shaped notch, spring tensioning means confined within the barrel and active upon the punch for projecting the same into the notch, a clamping screw fitting the body for axial alignment with and directly opposite the punch to be projected into the opening in said body, and means connected with the punch and exposed exteriorly of the barrel for retracting said punch against the tensioning means. 15 20 25 30
